US0D1063995S

(12) **United States Design Patent** (10) **Patent No.:** **US D1,063,995 S**
(45) **Date of Patent:** **** Feb. 25, 2025**

(54) **SNOWPLOW**

(71) Applicant: **Yongkang Haiwo Tools Co., Ltd.,**
Zhejiang (CN)

(72) Inventors: **Ren Hu**, Zhejiang (CN); **Yong Li**,
Hubei (CN)

(73) Assignee: **Yongkang Haiwo Tools Co., Ltd.,**
Jinhua (CN)

(**) Term: **15 Years**

(21) Appl. No.: **29/965,023**

(22) Filed: **Sep. 25, 2024**

(51) **LOC (15) Cl.** **15-02**

(52) **U.S. Cl.**

USPC **D15/11**

(57) **CLAIM**

The ornamental design for a snowplow, as shown and described.

DESCRIPTION

FIG. 1 is a first perspective view of a snowplow showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1; and,

FIG. 8 is a bottom plan view of FIG. 1.

The broken lines in the drawings depict portions of the snowplow that form no part of the claimed design.

1 Claim, 8 Drawing Sheets
